ELECTRIC LOCK

Herbert L. Bone, Forest Hills, Pa., assignor to The
Union Switch & Signal Company, Swissvale,
Pa., a corporation of Pennsylvania

Application December 10, 1943, Serial No. 513,707

11 Claims. (Cl. 246—159)

My invention relates to electric locks, and particularly to locks for preventing the unauthorized operation of railway traffic controlling devices such as switches, derails or the like.

One object of my invention is to provide an electric lock which may be used with any of the usual types of manually operable switch operating mechanisms, and which is capable of locking the mechanism in both its normal and its reverse positions.

Another object of my invention is to provide an electric lock which can be bolted directly to the housing of a switch operating mechanism of the type described and claimed in Letters Patent of the United States No. 2,184,870, granted to myself and another on December 26, 1939, whereby the necessity for separate tie mounting is eliminated along with the possibility of any shifting in relationship between the lock and the switch operating mechanism.

A further object of my invention is to provide an electric lock which does not require a lever lock rod.

According to a preferred form of my invention, the lock comprises a casing which is adapted to be secured to the housing of switch operating mechanism of the type described in Patent No. 2,184,870 referred to above, and which casing slidably receives one end of the lock bar of the switch operating mechanism. A lock member is mounted in the casing for movement between an intermediate and two extreme positions, and this member cooperates with electromagnetically controlled means which is effective when deenergized to prevent movement of the lock member from its intermediate to its one extreme position but not from its intermediate to its other extreme position. The lock member is operatively connected with a foot pedal and is biased to its intermediate extreme position. The foot pedal, in turn, is operatively connected with a lever latch which cooperates with the hand throw lever of the switch operating mechanism in such manner that the hand throw lever is prevented from being moved away from its normal extreme position except when the lever latch occupies an unlatching position corresponding to said one extreme position of said lock member. An auxiliary latch stand is provided with a foot pedal and lever latch similar to the foot pedal and lever latch of the lock proper, and the foot pedal of this stand is connected with the foot pedal of the lock in such manner that the foot pedal and latch of the stand are caused to operate in unison with the foot pedal and latch of the lock. The latch of the

- stand cooperates with the hand throw lever of the switch operating mechanism in such manner that the hand throw lever can be moved away from its reverse extreme position when and only when the lever latch of the stand occupies an unlatching position corresponding to said one extreme position of the lock member. The lock member is provided with means which cooperates with the lock bar of the switch operating mechanism to retain the latch members in their unlatching extreme positions when the hand throw lever is between its two extreme positions. Means are provided for padlocking the lever latches in their latching extreme positions.
- 10 In an alternative form of my invention the electric lock is adapted to be secured to one of the ties which support the railway switch rather than to the switch operating mechanism housing, and differs from the lock described above principally in the fact that an external lock rod operatively connected with the hand throw lever of the switch operating mechanism is used in place of the means secured to the locking member and cooperating with the lock bar of the switch operating mechanism to retain the lever latch of the lock and the lever latch of the latch stand in their unlatching position while the hand throw lever is being moved from either extreme position to the other.
- 15 Other objects and characteristic features of my invention will become apparent as the description proceeds.
- Electric locks embodying my invention are an improvement upon the electric lock shown and described in Letters Patent of the United States No. 1,126,834, granted to W. P. Neubert and W. E. Smith on February 2, 1915.
- 20 I shall describe two forms of electric locks embodying my invention, and shall then point out the novel features thereof in claims.
- 25 In the accompanying drawings, Fig. 1 is a top plan view showing a railway switch operated by a switch operating mechanism provided with a switch lock embodying my invention. Fig. 2 is an enlarged top plan view of the switch operating mechanism and lock shown in Fig. 1, the cover for the switch operating mechanism being removed to better illustrate some of the working parts of the mechanism. Fig. 3 is a vertical sectional view taken substantially on the line III—III of Fig. 2. Fig. 4 is a detail view of the motion plate of the mechanism shown in Figs. 2 and 3. 2, 3 and 5, taken substantially on the line VI—VI of Fig. 2. Fig. 7 is a sectional view taken substantially on the line VII—VII of Fig. 6. Fig. 8 is a top plan view with the cover removed of the lock shown in Figs. 6 and 7. Fig. 9 is an enlarged side view of the lever latch stand LLS forming part of the apparatus shown in Figs. 1 and 2. Fig. 10 is a view similar to Fig. 2 showing a modified form of lock embodying my invention. Fig. 11 is a front elevational view of the apparatus shown in Fig. 10. Fig. 12 is a sectional view of the modified form of lock shown in Figs. 10 and 11.

Similar reference characters refer to similar parts in each of the several views.

Referring first to Fig. 1, the reference character A designates a railway switch comprising, as usual, two fixed rails 1 and 1a and two movable rails or switch points 2 and 2a. The fixed rails 1 and 1a are laid on tie plates 3, and are secured to crossties 4 in the customary manner. The movable rails 2 and 2a are fastened together by a front rod 5 and a head rod 6, and may be moved into a normal or a reverse position by means of a throw rod 7 which is connected with the head rod 6 through the medium of a switch basket 8. When the switch occupies its normal position, in which position it is shown in the drawings, the movable rail 2 engages the fixed rail 1, and the movable rail 2a is spaced from the fixed rail 1a. When the switch is reversed, however, the movable rail 2a then engages the fixed rail 1a, and the movable rail 2 is spaced from the fixed rail 1.

Secured to an elongated pair of the ties 4 adjacent the outer side of the rail 1 is a switch operating mechanism B for operating the switch A. This mechanism in the form here shown is identical in all essential respects to that described and claimed in Letters Patent of the United States No. 2,184,870, granted to myself and another on December 26, 1939, and it is believed, therefore, that for the purpose of my present invention the following brief description of this mechanism will suffice.

As best seen in Figs. 2, 3 and 4, the mechanism B in the form illustrated comprises a suitable housing 10 which encloses the operating parts of the mechanism, and which is closed at its upper end by a removable cover 11. Located within the housing 10 is a motion plate 25 (see Fig. 4) which is guided to slide longitudinally in a direction parallel to the track by means of guide rollers 26 and 27, secured to the underside of the motion plate adjacent its opposite ends, and cooperating with guideways 28 provided on the bottom wall of the casing. The motion plate 25 has rack teeth 29 formed in its upper surface, which teeth mesh with a segment gear 30 mounted on a square shaft 31. The shaft 31 is mounted at its ends in bearing sleeves 32 and 33 journaled in bosses 34 and 35 formed in the sidewalls of the casing, and has secured thereto at its outer end adjacent to the sleeve 33 a hand throw lever 38 which serves as a means for reciprocating the motion plate between its two extreme positions.

A roller 40 is secured to the underside of the motion plate 25 adjacent one side thereof at a point equally spaced from the rollers 26 and 27, and this latter roller cooperates with cam faces 41 and 42 formed on an escapement crank 43 (see Fig. 2). The escapement crank 43 is formed integrally with the upper end of a switch actuating shaft 44, the shank of which is provided with two bearing surfaces 45 and 46 separated

5 by a squared portion 47. The bearing surfaces 45 and 46 are journaled in vertically aligned bearings 48 and 49 formed respectively in the bottom of the casing 10, and in a depending stirrup 50 which is provided on the underside of the casing, and secured to the square portion 47 of the shaft is a removable switch operating arm 50a which is pivotally attached to the free end of the throw rod 7.

10 A lock bar 51 extends longitudinally of the housing 10 directly above the motion plate 25, and is slidably mounted adjacent one end in a guideway 54 (see Fig. 3) formed in a frame 55 which is bolted to the housing adjacent its left-hand end, and which serves as a support for a circuit controller. The lock bar is operatively connected with the motion plate by means of a stud 57 secured to the lock bar and extending into a transversely disposed slot 58 formed in the upper side of the motion plate. The parts are so proportioned that when the casing 60 is secured to the casing 10, the stud 57 will be held in operative engagement with the motion plate.

20 The left-hand end of the lock bar 51 cooperates with a notch 59 provided in a lock rod L which is secured to the front rod 5 of the switch A. The parts are so proportioned that the notch 59 will align with the lock bar when and only when the switch occupies its full normal position, and that, when the notch 59 is in alignment with the lock bar, and the motion plate is in its left-hand extreme position, the lock bar will have entered the notch 59, as shown in Fig. 3, and will thus have locked the switch in its normal position.

30 The operation, as a whole, of the portion of the apparatus thus far described is as follows: When the hand throw lever 38 is rotated to its normal extreme position in which it is shown in the drawings, the motion plate 25 is moved to its extreme left-hand or normal position in which 35 it is shown in Figs. 2 and 3, and under these conditions, the switch points are held in their normal positions by engagement of the roller 40 with the cam surface 41 of the escapement crank 43. Furthermore, under these conditions, the lock bar 51 enters the notch 59 in the lock rod L, thus locking the switch points in their normal positions.

40 When it is desired to reverse the switch, the hand throw lever 38 is rotated in a counterclockwise direction through an angle of substantially 180° from the extreme position shown to its opposite or reverse extreme position. This rotation of the hand throw lever acts through the segment gear 30 and rack teeth 29 to move the motion plate to its right-hand extreme position, and as the motion plate moves to this latter position, the first part of the movement withdraws the lock bar 51 from the notch 59 in the lock rod L to unlock the switch; the intermediate 45 part of the movement causes the roller 40 to engage the cam surface 42 of the escapement crank 43 and rotate the escapement crank to the position in which the straight portion of the cam surface 42 extends parallel to the track, thereby rotating the switch actuating shaft to its reverse extreme position, and hence moving the switch points to their reverse extreme positions; while the final part of the movement of the motion plate causes the roller 40 to move along the straight portion of the cam surface 42 to such a

position that any tendency of the switch actuating shaft to rotate in a direction to permit the switch points to move away from their reverse positions is effectively blocked by the roller. It will be seen, therefore, that when the switch points occupy their reverse extreme positions, they are effectively held in these positions due to the coaction between the roller and the escapement crank, and it will also be seen that any force which may be exerted on the switch tending to restore it to its normal position will cause a transverse force to be exerted on the motion plate rather than a longitudinal force, thus avoiding any tendency to reverse the hand throw lever due to any force which may be exerted on the switch.

When the switch has been moved to its reverse position, and it is desired to restore it to its normal position, the hand throw lever 38 is returned to the position shown. The operation of the parts under these conditions is exactly the reverse of that just described, and this operation will be apparent from the foregoing description and from an inspection of the drawings without further detailed description.

Referring now to the electric lock embodying my invention, the casing 60 of this lock is closed at its upper end by a hinged cover 61 through which access to the interior of the casing may be had, and is provided at its forward side with an integral extension 62 formed with a jaw 63 (see Fig. 6) which receives the hand throw lever 38 when and only when the hand throw lever occupies its normal extreme position in which it is shown in the drawings. The extension 62 is also provided at one side with two spaced vertical standards 64 which support a pivot pin 65, and pivotally mounted on the pin 65 between the standards is a lever latch 66 (see Fig. 6). This latch is movable between a latching position in which it is shown in Fig. 6, and an unlatching position, and is provided with a nose portion 66a which, when the latch occupies its latching position, projects into the upper end of the jaw 63 in such manner that it prevents movement of the lever 38 into or out of the jaw, but which, when the latch is moved to its unlatching position, is withdrawn from the jaw. The latch is also provided with an eye 66b and with a treadle portion 66c. The eye 66b is so disposed that the bow of a padlock 67 (shown only in Fig. 6) can be inserted through the eye when and only when the latch occupies its latching position, and that, when the lock is in place in the eye, the bow of the lock will cooperate with the undersides of lips 64a formed on the standards 66 to lock the latch in its latching position. The treadle portion 66c of the latch provides a means for at times restoring the latch to its latching position following its movement to its unlatching position under certain conditions which will be made clear hereinafter.

Pivots mounted between the standards 64 below the latch 66 on another pin 68 is a foot pedal 69 provided with a finger 69a which projects into and cooperates with a recess 66d in the lower edge of the latch 66 in such manner that movement of the foot pedal will cause corresponding movement of the latch or vice versa. The foot pedal 69 is also provided with depending slotted bifurcations 69b which straddle one end of a rod 70 slidably mounted in the extension 62 of the casing 60 below the jaw 63. The foot pedal is operatively connected with the rod 70 by a pin 71 extending through the slots in 78

the bifurcations and through a clearance hole in the rod 70.

The inner end of the rod 70 is provided with a screw threaded portion 70a of reduced diameter, and screwed onto this portion is a block 72 which is pivotally connected by a pin 73 with a jaw 74a provided on the lower end of a locking segment 74. The locking segment 74 is also provided with a sleeve portion 74b by means of which it is mounted to rock on a rod 75 secured in a fixed position in the housing 60. The upper surface of the segment 74 is provided with a notch or recess 77 adapted to coact with a locking dog 78. This notch is elongated to permit the segment to rock through a limited angle when the dog 78 is in locking position for a purpose hereinafter explained. The dog 78 is formed on one end of a bar 79, the other end of which is secured to one end of an angle lever 80. The angle lever 80 is pivotally supported on pivot pins 81 mounted in depending lugs 82a provided on a supporting strap 82 secured by means of screws 83 to a magnet bracket 84, and its other arm carries an armature 85 adapted to be attracted by an electromagnet 86 mounted in the bracket 84. When the armature 85 is attracted by the electromagnet, it lifts the dog 78 out of the notch 77, thereby leaving segment 74 free to rock between its two extreme positions, but when the armature is released, the dog 78 drops onto segment 74 and into the notch 77 if the latter is in alignment therewith.

The locking segment 74 is further provided with a lateral arm 90 terminating at its free end in a depending portion 91 which cooperates with two holes 51a and 51b disposed in longitudinally spaced relation in the lock bar 51 in such positions that the hole 51a will align with the depending portion 91 when and only when the hand throw lever 38 occupies its normal extreme position, and that the hole 51b will align with the depending portion 91 when and only when the hand throw lever occupies its reverse extreme position. The parts are so proportioned that when either one of the holes 51a or 51b is in alignment with the depending portion 91 on the locking segment, the locking segment will be free to rotate to the extreme position shown, but that when the holes are out of alignment with the depending portion, the depending portion will cooperate with the upper surface of the locking bar to hold the locking segment in the extreme position it occupies when the lever latch is moved to its unlocking position.

The sliding rod 70 is not mounted directly in the casing 60, but slides in a sleeve 87 screwed into an opening provided in the casing 60. Slidably supported on the reduced portion 70a of the rod 70 between the sleeve 87 and the inner end 60 of the block 72 are two spring guides 92 and 93 which support a coil spring 94. The spring 94 is provided with sufficient initial compression so that it constantly urges the guides apart to the relative positions in which the guide 92 engages the inner end of the sleeve 87 and the guide 93 engages the adjacent end wall of a compartment 95 in which the spring and spring guides are disposed, and the parts are so proportioned that when the guides are in the relative positions just mentioned and the rod 70 is in its mid stroke position, the shoulder formed at the junction of the reduced portion 70a of the rod with the main body portion of the rod will just touch the guide 92 and the inner end of the sleeve will just touch the guide 93. It will be apparent, therefore, that

the spring 94 acts through the spring guides 92 and 93 to bias the rod 78 to its mid stroke position, and hence biases the foot pedal 69 and lever latch 66 to their mid stroke positions.

The notch 77 in the segment 74 is of sufficient length so that when the padlock is removed from the lever latch, the locking segment will be free to move, due to the bias of the spring 94, from the extreme position shown to its intermediate position even though the dog 78 is within the notch 77.

Attached to one side of the segment 74 is a cam 100 which coacts with a depressor arm 101 pivotally mounted at 102 in a lug 103 secured to the underside of a terminal board 104 of insulating material, which latter, in turn, is mounted on supports extending upwardly from the magnet bracket 84. When the locking segment occupies its normal extreme position as shown in Fig. 6, the cam 100 is out of engagement with the arm 101, and under these conditions the arm is held in a lowered position both by the force of gravity, and by the bias of a compressed coil spring 129 which is disposed between the upper side of the arm and a plate 121 overlying a hole 122 in the terminal board. When, however, the locking segment is swung from the normal extreme position shown to its intermediate or its other extreme position, the cam 100 engages the arm 101 and forces it to an upper position for a purpose to be made clear presently. The plate 121 is secured to the upper side of the terminal board 104 by means of the same screw which fastens the lug 103 to the terminal board, as will be obvious from an inspection of the drawings.

A contact operating bracket 108 (see Fig. 7) provided with three flexible contact fingers 111 is suspended from the terminal board 104 by means of three flexible supporting springs 109 one end of each of which is secured to the upper side of the bracket in electrical contact with an associated one of the contact fingers, and the other end of each of which is secured to the underside of the terminal board 104 by means of an associated terminal post 110. It will be seen, therefore, that each contact finger is electrically connected to an associated one of the terminal posts 110 through the medium of the associated supporting spring 109. The bracket 108 is operatively connected with the depressor arm 101 through the medium of an operating arm 107 in such manner that the bracket will be moved to a raised or a lowered position according as the depressor arm is moved to its raised or lowered position, and the two outside contact fingers cooperate with two fixed contact members 112 secured to terminal posts 113 mounted on the terminal board 104 to close or open back contacts 111-112 according as the depressor arm occupies its lowered or raised position, while the middle finger cooperates with a fixed contact member 114 secured to a terminal post 115 mounted on the terminal board 104 to close or open a front contact 111-114 according as the depressor arm occupies its raised or its lowered position. The contact member 111-114 is intended to be connected in series with the electromagnet winding, and serves to prevent this winding from becoming energized unless the parts are in the position in which the contact 111-114 becomes closed.

The operating arm 107 is secured at one end to the underside of the bracket 108, and is provided at the other end with a slot which receives a V grooved bushing 105 of insulating material secured by means of a screw 106 to the upper side

of the arm 101. A flat spring 116 of suitable flexibility is clamped to arm 101 underneath the bushing 105, and cooperates with the arm 79 in such manner that when the arm 101 occupies its lowermost position and the magnet 86 is de-energized, sufficient force will be transmitted through the spring 116 to the arm 79 to prevent vibration of the parts. Spring 116 is raised by arm 101 out of engagement with arm 79 before magnet 86 can be energized, and therefore does not exert any force on the armature 85 opposing its movement to its attracted position when the magnet 86 becomes energized.

The armature 85 also controls other contacts 117-118 in such manner that these contacts will be open or closed according as the armature is released or picked up. These contacts may be used to provide an indication at a remote point of the energized or deenergized condition of the lock or for any other desired purpose.

The apparatus also includes means embodying my invention to enable the electric lock to be used to lock the switch in its reverse position as well as in its normal position. As here shown, these means comprise a lever latch stand LLS (see Figs. 2, 5 and 9) bolted to one of the ties 4 on the same side of the mechanism B as the hand throw lever 38, and provided with a jaw 163 which receives the hand throw lever 38 when it is operated to its reverse position in the same manner that the jaw 63 in the extension 62 on the electric lock receives the hand throw lever 38 when the hand throw lever occupies its normal position. The latch stand is formed with standards 164 corresponding to the standards 64 on the lock, and has pivoted therein between the standards on suitable pivot pins 165 and 168 a lever latch 166 and a foot pedal 169. The lever latch 166 and foot pedal are identical with the lever latch 66 and foot pedal 69 of the lock, and the two foot pedals 69 and 169 are mechanically connected together to cause them to operate in unison by means of a rocker shaft 125 provided at its opposite ends with cranks 126 and 127 respectively. The rocker shaft is pivoted at its ends on the heads of the pivot pins 68 and 168, and the two cranks extend through apertured lugs 69c and 169c provided on the foot pedals.

The operation of the apparatus as a whole is as follows: When the switch A and the switch operating mechanism B occupy their normal positions as shown in Fig. 1, the parts of the electric lock occupy the positions in which they are shown in Figs. 6, 7 and 8. That is to say, the padlock is inserted into the eye 66b of the lever latch 66 so that this lever latch and the foot pedal 69 are held in their normal positions in opposition to the bias of the centering spring 94, the locking segment 74 occupies its normal position in which the depending portion 91 of the arm 90 is within the hole 51a in the lock bar 51, the electromagnet 86 is deenergized so that armature 85 is released and dog 78 is within the notch 77, and cam 100 is out of engagement with depressor arm 101 so that the contacts 111-112 are closed and contact 111-114 is open.

I shall now assume that it is desired to operate the switch to its reverse position. To do this, the padlock 67 is first removed from the eye 66b. This permits the spring 94 to move the rod 78 to its intermediate position which movement, in turn, moves the foot pedals 69 and 169, the lever latches 66 and 166 and the locking segment 74 to their intermediate positions. The movement 75 of the locking segment 74 to its intermediate po-

sition acts through the medium of the cam 100 and depressor arm 101 to open the contacts 111-112 and to close the contacts 111-114, and if traffic conditions are then such that it is safe to operate the switch as determined by the external control circuit which it is intended will be provided for magnet 86, this magnet will automatically become energized. One form of control circuit which may, for example, be used to control the energization of the magnet 86 is shown in Fig. 4 of Patent No. 1,126,834 referred to hereinbefore. Assuming that magnet 86 does become energized, the locking dog 78 will be lifted out of the notch 77 in the locking segment, to unlock the locking segment, and the contacts 117-118 will become opened. With the locking segment unlocked, the operator may depress foot pedal 69, whereupon latch 66 will be swung clear of the path of movement of the hand throw lever 38 out of the jaw 63 and the extension 91 on the arm 90 of the locking segment 74 will be swung out of the hole 51a in the lock bar 51. The lever latch 166 will also be swung out of the path of movement of the hand throw lever 38 into the jaw 163 in the lever latch stand LLS. Since the lever latches 66 and 166 are now both out of the path of movement of the hand throw lever, the hand throw lever may be operated to reverse the switch points in the usual manner, as described hereinbefore. As soon as the operator starts to move the hand throw lever, the hole 51a in the lock bar 51 will move out of alignment with the depending portion 91 on the arm 90 of the locking segment, and, as a result, the foot pedal 69 may then be released and the engagement of the depending portion 91 with the top of the lock bar will act to hold the parts of the lock in the positions they then occupy so that the lever 38 will be free to enter either the jaw 63 or the jaw 163 without interference from the lever latches. When the hand throw lever reaches its full reverse position, the hole 51b in the lock bar will then move into alignment with the depending portion 91 on the arm 90 of the locking segment and will thus permit the spring 94 to return the parts of the lock to their intermediate positions. If, now, it is desired to lock the switch in its reverse position, the operator will depress the lever latch 166, by placing his foot on the treadle portion 166a thereof, and will then insert the padlock 67 in the eye 166b of the lever latch 166. Inasmuch as the parts of the lever latch stand and the parts of the electric lock are caused to operate in unison, the parts of the electric lock will be restored to their normal positions and will be subsequently held there as long as the switch remains locked in its reverse position.

When it is desired to again restore the parts to the positions shown, the padlock is removed from the eye 166b in the lever latch 166, and the foot pedal 169 is then depressed. The removal of the padlock permits the spring 94 of the electric lock to move the parts of the lock and the lever latch stand to their intermediate positions, and causes the electromagnet 86 to become energized in the same manner as was described hereinbefore when the lock was removed from the eye 166b of the lever latch 66, while the depression of the foot pedal 169 moves both lever latches to their unlatching positions. As soon as the latches are moved to their unlatching positions, the hand throw lever 38 may then be operated to its normal position in the usual manner. During the operation of the hand throw lever, both notches 51a and 51b in the lock bar will be out of alignment

with the depending portion 91 on the arm 90 of the electromagnet, and as a result the lever latches will be retained in their unlatching positions even though the operator removes his foot 5 from the foot pedal 169 as soon as he has moved the hand throw lever a short distance from its reverse extreme position. When the hand throw lever is restored to its full normal position, hole 51a in the lock bar 51 will move into alignment with the depending portion 91 on the arm 90, and the spring 94 will then act to restore the parts of both the lock and the latch stand to their intermediate positions. Magnet 86 will thereupon become deenergized due to the resultant opening of contact 111-112. As soon as the depending portion 91 enters the hole 51a in the lock bar 51, the lever latch may be depressed to its latching position, and the padlock 67 inserted in the eye 166b. When this is done, all parts will be restored to their normal positions in which they are shown in the drawings.

Referring now to Figs. 10, 11 and 12, the lock EL here shown is adapted to be bolted to the ties instead of to the end of the housing of the switch 25 operating mechanism B, and differs from the lock previously described principally in the fact that an external lock rod 190 is used in place of the arm 90 on the locking segment 74 cooperating with the lock bar 51 to retain the lever latch in its 30 unlatched position while the hand throw lever 38 is in transit. One end of the rod 190 is pivoted on a stud 191 mounted on the hub of the hand throw lever 38 on the vertical center line of the hand throw lever shaft below the axis of the 35 shaft, and the other end is loosely supported to slide in an opening 192 (see Fig. 12) in one of the standards 64 of the electric lock in close proximity to the finger 69a. When the lever latch 66 is moved sufficiently to clear the hand throw lever 40 by depressing the foot pedal 69, the finger 69a will have moved out of the path of the rod 190, and then when the lever 38 is swung upwardly, the rod 190 will be moved endwise behind the 45 finger 69a as viewed in Fig. 12, and will thus act to retain the foot pedal in its depressed position and the latch in its unlatched position in opposition to the bias of the spring 94 until the hand throw lever is moved to one extreme position or 50 the other. It will be seen, therefore, that with the lock constructed as shown in Figs. 10, 11 and 12, the lock rod 190 performs the same function as is performed by the arm 90 and the holes 51a and 51b in the lock bar of the electric lock shown in Figs. 6, 7 and 8.

The lock as shown in Figs. 10, 11 and 12 is further provided with an anti-rattler spring 193 mounted on one end of the pin 65 on which the lever latch 66 is pivoted. One end of this spring is anchored to a pin 194 projecting from one of the standards 64 below the pin 65, and the other end engages a lug 66e provided on the side of the lever latch 66. The spring 193 is assembled in such manner that it tends to rotate lever latch 66 in a clockwise direction as viewed in Fig. 12, and consequently tends to rotate foot pedal 69 in a counterclockwise direction, whereby it assists spring 94 when the parts are in their latching positions.

The apparatus shown in Figs. 10, 11 and 12 70 also comprises a lever latch stand LLS for locking the lever in the reverse position. This latch stand is similar to the latch stand LLS previously described except for the fact that it is provided with an anti-rattler spring 194 similar to the spring provided in the lock proper. The latch

stand is connected with the lock proper in a manner similar to that previously described in connection with the form of the invention shown in Figs. 1, 2 and 5. The anti-rattler spring 194 is assembled so that it tends to bias the lever latch 166 to its locking position, and the parts are so proportioned that the forces exerted by the two anti-rattler springs on the lever latches will balance each other. It follows, therefore, that the anti-rattler springs do not interfere with the normal function of the lock but do act to prevent wear due to vibration.

The operation of the apparatus shown in Figs. 10, 11 and 12 as a whole is similar to the previously described operation of the apparatus shown in the preceding views, and it is believed to be unnecessary, therefore, to refer to it in further detail herein.

If desired, anti-rattler springs similar to those just described may be applied to the form of the lock shown in Figs. 1 to 9, inclusive.

Under some conditions it may be desirable to lock the switch in its normal position only. When this is the case, the form of the apparatus shown in Figs. 1 to 9, inclusive, may be adapted to this purpose by omitting the hole 51b in the lock bar 51 and the latch stand LLS. With the hole 51b and the latch stand LLS eliminated, the lock can be locked up when and only when arm 90 aligns with hole 51a, which will occur when and only when the switch is locked in the normal position.

One advantage of apparatus embodying my invention is that it permits a hand operated switch to be electrically locked in both its normal and reverse positions by means of a single electric lock.

Although I have herein shown and described only two forms of electric locks embodying my invention, it is understood that various changes and modifications may be made therein within the scope of the appended claims without departing from the spirit and scope of my invention.

Having thus described my invention, what I claim is:

1. The combination with a switch operating mechanism including a hand throw lever movable between normal and reverse positions for moving an associated switch between corresponding extreme positions, of two lever latches each movable between a latching and an unlatching position, one said latch cooperating with said lever to prevent its movement away from its normal extreme position except when said one latch occupies its unlatching position and the other said latch cooperating with said lever to prevent its movement away from its reverse extreme position except when said other latch occupies its unlatching position, means for operating said latches to their unlatching positions, means connecting said two latches together to cause them to operate in unison, and electromagnetically controlled means associated with one of said latches and effective when deenergized to prevent movement of said latches to their unlatching positions.

2. The combination with a switch operating mechanism including a hand throw lever movable between normal and reverse positions for moving an associated switch between corresponding extreme positions, of two lever latches each movable between a latching and an unlatching position, one said latch cooperating with said lever to prevent its movement away from its normal extreme position except when said one latch occupies its unlatching position and the other said

latch cooperating with said lever to prevent its movement away from its reverse extreme position except when said other latch occupies its unlatching position, means for operating said latches to their unlatching positions, means connecting said two latches together to cause them to operate in unison, electromagnetically controlled means associated with one of said latches and effective when deenergized to prevent movement of said latches to their unlatching positions, and means for locking said latches in their latching positions.

3. In combination, a switch operating lever movable between a normal and a reverse position, two lever latches each movable between latching and unlatching positions, one said latch being effective in its latching position to prevent movement of said lever to or away from its normal extreme position, and the other said latch being effective in its latching position to prevent movement of said lever to or away from its reverse extreme position, means connecting said latches together to operate in unison, means biasing said latches to intermediate positions, a contact operated when said latch is operated from its latching to its intermediate position, and electromagnet means energizable over said contact, said electromagnetic means being effective when de-energized to permit movement of said latches from their latching positions to their intermediate positions and to prevent movement of said latches to their unlatching positions and being effective when energized to permit movement of said latches to their unlatching positions.

4. In combination, a switch operating lever movable between normal and reverse positions, two lever latches each movable from a latching position through an intermediate position to an unlatching position, one said latch being effective in its latching position to prevent movement of said lever to or away from its normal position and the other said latch being effective in its latching position to prevent movement of said lever to or away from its reverse position, two foot pedals pivoted on aligned pivot pins and one operatively connected with each of said latches, each said foot pedal being provided with an apertured lug, a rockshaft journaled at its ends on said pivot pins and provided with two cranks one engaging each of said foot pedals at said apertured lugs, and electromagnetically controlled means associated with one of said latches and effective to prevent or permit movement of said latches to their unlatching positions according as said means is deenergized or energized.

5. In combination, a switch operating lever movable between normal and reverse positions, two lever latches each movable from a latching position through an intermediate position to an unlatching position, one said latch being effective in its latching position to prevent movement of said lever to or away from its normal position and the other said latch being effective in its latching position to prevent movement of said lever to or away from its reverse position, two foot pedals pivoted on aligned pivot pins and one operatively connected with each of said latches, each said foot pedal being provided with an apertured lug, a rockshaft journaled at its ends on said pivot pins and provided with two cranks one engaging each of said foot pedals at said apertured lugs, means biasing said foot pedals to intermediate positions, a contact operated when either foot pedal is moved from its latching to an intermediate position, and electromag-

netic means energizable over said contact, said electromagnetic means being effective when de-energized to permit movement of said latches from their latching to their intermediate positions and to prevent movement of said latches to their unlatching positions and when energized to permit movement of said latches to their unlatching positions.

6. In combination, a switch operating lever movable between normal and reverse positions, two lever latches each movable from a latching position through an intermediate position to an unlatching position, one said latch being effective in its latching position to prevent movement of said lever to or away from its normal position and the other said latch being effective in its latching position to prevent movement of said lever to or away from its reverse position, two foot pedals pivoted on aligned pivot pins and one operatively connected with each of said latches, each said foot pedal being provided with an apertured lug, a rockshaft journaled at its ends on said pivot pins and provided with two cranks one engaging each of said foot pedals at said apertured lugs, means biasing said foot pedals to intermediate positions, a contact operated when either foot pedal is moved from its latching to an intermediate position, electromagnetic means energizable over said contact, said electromagnetic means being effective when deenergized to permit movement of said latches from their latching to their intermediate positions and to prevent movement of said latches to their unlatching positions and when energized to permit movement of said latches to their unlatching positions, and two anti-rattler springs one connected to each of said latches, said springs being so disposed that the net forces exerted thereby on said latches neutralize each other.

7. In combination, a switch operating lever operable between normal and reverse positions, a first latch movable between latching and unlatching positions and effective when in its latching position to prevent movement of said lever away from its normal position, a locking member operatively connected with said first latch and movable between an intermediate and two extreme positions, electromagnetic means cooperating with said locking member in such manner that when said means is deenergized it permits movement of said member between said intermediate position and one extreme position but not to the other extreme position unless the magnet is energized, a contact controlled by said locking member and closed or open according as said locking member occupies said intermediate position or said other extreme position, said contact controlling the energization of said electromagnet, a first foot pedal connected with said first latch for moving it to its unlatching position, a latch stand including a second latch movable between latching and unlatching positions and effective when in its latching position to prevent movement of said lever away from its reverse position, a second foot pedal operatively connected with said second latch for moving it to its unlatching position, and means connecting said two foot pedals together to cause them to operate in unison, whereby both latches are prevented from being moved to their unlatching positions unless said electromagnet is energized.

8. The combination with a switch operating mechanism including a hand throw lever movable between two extreme positions for moving a switch between its two extreme positions and a

lock bar movable to a locking position, of an electric lock comprising a casing secured to said switch operating mechanism and receiving one end of said lock bar for locking the switch in its one extreme position, a locking member mounted in said casing for movement between an intermediate and two extreme positions, means for biasing said locking member to its intermediate extreme position, a contact controlled by said locking member and operated by movement of said locking member away from its one extreme position, electromagnetic means energized over said contact and cooperating with said locking member in such manner that movement of said locking member between said one extreme position and its intermediate position is permitted and movement to its other extreme position is prevented when said means is deenergized but that movement of said locking member to its other extreme position is permitted when said means is energized, means for moving said locking member to its other extreme position, a latching member operatively connected with said locking member through the medium of said last mentioned means and movable to a latching or an unlatching position according as said locking member occupies its one or its other extreme position, said latching member being effective when in its latching position to prevent movement of said lever away from its one extreme position, and means controlled by said lock bar for retaining said latching member in its unlatching position when said hand throw lever is moved away from its one extreme position.

9. The combination with a switch operating mechanism including a hand throw lever movable between two extreme positions for moving a switch between its two extreme positions and a lock bar movable to a locking position, of an electric lock comprising a casing secured to said switch operating mechanism and receiving one end of said lock bar for locking the switch in its one extreme position, a locking member mounted in said casing for movement between an intermediate and two extreme positions, means for biasing said locking member to its intermediate extreme position, a contact controlled by said locking member and operated by movement of said locking member away from its one extreme position, electromagnetic means energized over said contact and cooperating with said locking member in such manner that movement of said locking member between said one extreme position and its intermediate position is permitted and movement to its other extreme position is prevented when said means is deenergized but that movement of said locking member to its other extreme position is permitted when said means is energized, a foot pedal operatively connected with said locking member for moving it, a first latching member operatively connected with said locking member through the medium of said foot pedal and movable to a latching or an unlatching position according as said locking member is moved to its one or its other extreme position, said first latching member being effective when in its latching position to prevent movement of said hand lever away from its one extreme position, a latch stand including a second latching member movable between latching and unlatching positions and operatively connected with a second foot pedal for moving said second latching member, means connecting said two foot pedals together to cause them to oper-

ate in unison, and means controlled by said lock bar for retaining both said latching members in their unlatching positions when said lever is between its two extreme positions.

10. The combination with a switch operating mechanism including a hand throw lever movable between two extreme positions for moving a switch between two extreme positions and a lock bar movable to a locking position when and only when said switch occupies its one extreme position, of an electric lock comprising a casing secured to said switch operating mechanism and receiving one end of said lock bar, a latch pivotally attached to said casing for movement between a latching and an unlatching position and effective when in its latching position to prevent movement of said lever away from its one extreme position, a foot pedal pivotally attached to said casing and operatively connected with said latch, a locking segment pivotally mounted in said casing and operatively connected with said foot pedal, said locking segment being movable to one extreme position or another according as said latch is moved to its latching or its unlatching position, means biasing said locking segment and connected parts to intermediate positions, a contact, means operated by movement of said locking segment away from its one extreme position for operating said contact, electromagnetic means energized over said contact, said electromagnetic means being effective when deenergized to permit movement of said locking segment between its one extreme position and its intermediate position but to prevent movement past its intermediate position toward its other extreme position and when energized to permit movement of said locking segment to its other extreme position, an arm secured to said locking segment and provided with a depending portion cooperating with said lock bar, said lock bar being provided with a hole which aligns with said depending portion when and only when said bar occupies its locking position, the parts being so proportioned that when said hole is in alignment with said depending portion said segment is free to move to its one extreme position but that when said hole is out of alignment with said depending portion said depending portion will cooperate with the top of said bar to retain said latch in its unlatching position.

11. The combination with a switch operating mechanism including a hand throw lever movable between two extreme positions for moving a switch between two extreme positions and a lock bar movable to a locking position when and only when said switch occupies its one extreme position, of an electric lock comprising a casing secured to said switch operating mechanism and receiving one end of said lock bar, a latch pivotally attached to said casing for movement between a latching and an unlatching position and effective when in its latching position to prevent movement of said lever away from its one extreme position, a foot pedal pivotally attached to said casing and operatively connected with said latch, a locking segment pivotally mounted in said casing and operatively connected with said foot pedal, said locking segment being movable to one extreme position or another according as said latch is moved to its latching or its unlatching position, means biasing said locking segment and connected parts to intermediate positions, a contact, means operated by movement of said locking segment away from its one extreme position for operating said contact, electromagnetic means energized over said contact, said electromagnetic means being effective when deenergized to permit movement of said locking segment between its one extreme position and its intermediate position but to prevent movement past its intermediate position toward its other extreme position and when energized to permit movement of said locking segment to its other extreme position, an arm secured to said locking segment and provided with a depending portion cooperating with said lock bar, said lock bar being provided with a hole which aligns with said depending portion when and only when said bar occupies its locking position, the parts being so proportioned that when said hole is in alignment with said depending portion said segment is free to move to its one extreme position but that when said hole is out of alignment with said depending portion said depending portion will cooperate with the top of said bar to retain said latch in its unlatching position, and means for locking said latch in its latching position.

HERBERT L. BONE.
